UNITED STATES PATENT OFFICE.

ROBERT L. LYONS, OF WALTHAM, MASSACHUSETTS, ASSIGNOR TO FREDERICK OSANN COMPANY, OF NEW YORK, N. Y., A CORPORATION OF NEW YORK.

SEWING-MACHINE.

1,302,394.

Specification of Letters Patent. Patented Apr. 29, 1919.

Application filed January 19, 1916. Serial No. 72,922.

To all whom it may concern:

Be it known that I, ROBERT L. LYONS, of Waltham, in the county of Middlesex and State of Massachusetts, a citizen of the 5 United States, have invented certain new and useful Improvements in Sewing-Machines, of which the following is a specification, reference being had to the accompanying drawings, forming part thereof.

10 This invention has reference to improvements in sewing machines of the general nature referred to in my application for Letters Patent of the United States Serial No. 660,593, filed November 16, 1911, of which 15 the present application is a continuation in part.

One object of the invention is to provide a sewing machine with complementary thread breaking devices adapted to break the thread 20 and so constituted that one of said complementary thread breaking devices may be operated by means actuated through the driving mechanism for the stitch forming devices and the other of said complementary 25 thread breaking devices may be operated independently of said driving mechanism.

Another object of the invention is to so construct a sewing machine of this nature having complementary thread breaking devices of the nature described that at about 30 the completion of the sewing of a group of stitches one of said complementary thread breaking devices is actuated, through means operating in conjunction with the driving 35 mechanism, to resist the movement of the thread so that at some time thereafter and usually after the movement of the stitch forming devices has ceased, the other of said complementary thread breaking devices may 40 be operated to break the thread.

Another object of the invention is to so construct a thread breaking mechanism having complementary thread breaking devices both located above the work, that both of 45 said devices may be operated positively but independently and that the actuator of one of said devices may have a retractive movement assisted by a spring.

Other objects of the invention will appear from the following description.

The invention consists in such novel features of construction and combination of parts as shall hereinafter be more fully described and pointed out in the claims.

55 Figure 1, represents a side elevation of

parts of a single thread button sewing machine having the improved thread breaking devices, parts of the same being broken away and other parts being shown in section.

Fig. 2, represents a sectional view of the 60 same as taken on line 2—2 Fig. 1.

Similar characters of reference designate corresponding parts throughout.

The invention herein disclosed and forming a part of the invention referred to in 65 my application Serial No. 660,593, above mentioned, is particularly applicable to single thread sewing machines having means to sew groups of stitches as in the sewing of buttons to material. In this art 70 it is well known that the stitch forming devices are operated for a predetermined number of movements or during a predetermined time to produce a series or group of attaching stitches, and that during a part 75 at least of such operation relative movement is effected between the stitch forming devices and the work, herein understood to be a button and the material to which said button is to be sewn. It is also well known that, 80 in single thread sewing machines the arrest of the work from feeding movement while the operation of the stitch forming devices continues will result in the formation of a chain beneath the work and that if said 85 chain be drawn tight against the work a knot, so called, will result. In my present invention I make use of a machine of the nature just above referred to whereby a series or group of stitches is sewn and at the 90 completion of said group of stitches relative movement between the stitch forming devices and the work ceases while the stitch forming devices continue to operate to make one, two or more tying or knotting chain 95 stitches, so called, after which the mechanism is brought to a stop with the thread extending from said chain stitches down to and around the looper and thence up through the work, through the needle and through 100 various guides to the spool or bobbin.

In the drawings I have shown my present invention as applied to a machine of the description referred to above. This showing being for the purpose of illustration is not 105 restrictive. The machine shown has the bed 5 in bearings of which is journaled the shaft 6 through which the stitch forming devices, the looper L and the needle N with their connections, of any usual construction are 110

operated in any known manner. On this shaft 6 is mounted the worm 7 which drives the worm gear 8 and made in part with or secured to the cam 10 which latter is journaled on the stud 11 depending from base 5 and has the usual cam groove 12 of any usual shape to effect the vibration of the follower 13 having the dwell or concentric path 14. This dwell portion 14 of the cam groove 12 preferably is of a length to operate relative to the follower 13 while the stitch forming devices are making one, two or three stitches.

Follower 13 is mounted on the arm 15 of the vertical shaft 16 which is journaled in a bearing of the bed 5 and at its upper end portion is connected by the arm 17 and the usual connections with a button clamp of well known construction having the button carrying member 18 so mounted that it may be moved upward or at least away from the looper L at times. This operation of the button clamp or member from the follower 13 is that usually employed to effect relative movement between the button or work and the stitch forming devices in making a group of button sewing stitches and it is evident that it may be utilized for this purpose.

The needle N is carried by a needle bar 19 which with its operating mechanism is mounted in or on the machine head 20 carried by the base 5, said operating mechanism being of any known kind preferably to be driven from the shaft 6 in some manner.

The machine thus described, as stated above, is of well known construction not in itself invented by me but herein shown and described to illustrate my invention with which said machine is adapted to operate.

In bearings carried by the head 20 is journaled the rock shaft 21 having the lifter arm 22, connected with the button clamp 18 by the chain 23 to lift the free end of said button clamp when said shaft 21 is suitably rocked by the swinging of its lever 24 which lever 24 is adapted to be manually actuated. On said rock shaft 21 are preferably mounted the stop sleeve 25 and the thread puller arms 26 and 27. Said arms 26 and 27 do not in their specific location or construction form part of my present invention; therefore said arms are merely indicated.

Mounted on the top of the head 20 at a distance back of the needle bar 19 is the thread tension 28 and the thread guide 29 and between these parts, on said head 20, is mounted the post 30 and the thread clamp member 31 while on said post 30 is pivotally mounted the thread clamp member 32 adapted to coöperate with the member 31 to clamp the thread *a—b* which passes between these members 31 and 32 in the feeding movement of said thread toward the

needle N and looper L. A spring 33 is provided which acts to swing the thread clamp member 32 in one direction and provision is made to move said clamp member 32 against the action of its spring; such provision is the rod 34 which is slidably mounted in guides of the machine and has the head or member 35 adapted to act against the thread clamp member 32 and the end or element 36. In order to limit the retractive movement of rod 34 I prefer to supply the same with the pin 37 the downward movement of which is arrested by the stop sleeve 25 of rock shaft 21 whereby the end or member 36 of said rod 34 is sustained slightly out of contact with the surface of the gear 8.

The lifting of said rod 34 as an instrumentality for effecting the clamping or nipping of the needle thread at a predetermined time relative to the operation of the machine as well as to the proposed stopping of the machine is accomplished by the cam or member 9 of the gear 8 which is located on said gear 8 in such relation to the dwell 14 of the cam groove 12 of cam 10 that said member 9 acts to lift said rod 34 at a time when, in the rotation of said cam 10, the follower 13 is in the cam dwell 14 at a time at which said cam 10 has nearly completed its rotation. The purpose of the cam groove or way 12 having the dwell 14 and coöoperating with the follower 13 to effect the vibration of the button clamp or work holder having been known prior to my invention I would state briefly that the operation of rod 34 to effect the clamping of the thread during the formation of a group of sewing stitches, or at the completion of said group of sewing stitches should be avoided and that the operation of clamping the thread should occur preferably only after at least the partial formation of a tying stitch.

In preparing this machine for operation the thread *a—b* is threaded through the various guide eyes and the eye of the needle N in the usual manner but, in addition, extends between the members 31 and 32 of the thread clamping or thread restraining device. A button is placed in the button clamp 18 and a piece of material is placed beneath the button as heretofore.

The machine is supplied with any usual driving means adapted to effect a predetermined number of rotations of shaft 6 and, through said shaft, a predetermined number of operations of the stitch forming devices which number of rotations may be varied in different kinds of work or may depend upon adjustment of the parts. At the completion of such operation the stitch forming devices are usually arrested with the needle N in or approximately in the raised position. The groove 12 of cam 10 has usually a number of throws or active members to effect the vibration of the fol-

lower 13 and, through said follower, the button clamp 18 a number of times dependent somewhat on the number of attaching stitches to be made but the length of the 5 concentric portion or dwell 14 of said groove may be the same in all such cases.

The machine having been started the stitch forming devices are operated and the button clamp 18 is vibrated while the waved portion of cam groove 12 is traveling by said follower 13 but when the dwell 14 of said groove 12 receives said follower 13 the vibration of said follower and of the button clamp and the work carried by said clamp ceases 10 so that the continued operation of the stitch forming devices results in the formation of one or more chain stitches. During such sewing operation and the formation of such chain stitches the thread $a-b$ is free to feed 15 toward and supply thread to the needle, said thread being controlled in such feeding movement mainly by the usual tension devices. Thus, as the predetermined number 20 of attaching stitches and chain stitches approaches completion the thread $a-b$ will not be under any strain unnecessary for the sewing operation.

At or about the time of making of the last chain stitch the cam 9 of the rotating 30 member 8 will ride beneath the element 36 of rod 34 and will raise said rod and thereby move the thread clamp member 32 to clamp or press the thread $a-b$ against the thread clamp member 31, said cam 9 holding 35 said slide rod 34 against retraction until the thread is broken. Practically simultaneously with such clamping or engaging of the thread $a-b$ between the members 32 and 31 the operation of the machine will cease.

40 The unbroken thread will now extend between the clamp members 32, 31 which will be a point of restraint on the thread, through the usual guides, through the needle N, through the work held by button clamp 18, 45 down and around the looper L and up to the work to which said thread will be attached by the chain stitches above referred to, thus completing the operation whereby the thread may subsequently be broken.

50 At a time after the stopping of the machine, determined by the will of the operator, lever 24 may be swung to partially rotate shaft 21 and to actuate arm 22 to lift chain 23 and the movable end of button clamp 18 which button clamp will lift the work with the result that a strain will be put upon the thread $a-b$ which strain being resisted at the point of restraint defined by the clamp members 32, 31 will first cause 55

60 the chain stitches at the work to be tightened somewhat and, if such upward movement of the work is continued, will ultimately cause the breaking of the thread at the tightened chain or tying stitches, leaving the length of 65 thread which had, before such breaking, ex-

tended around the looper and back to the needle as a long starting end whereby the next sewing operation can be started without rethreading the needle.

When the machine is again started cam 10 70 is operated through its gear 8 and during the first downward movement of the needle the cam or actuator member is moved to release rod 34 so that said rod may move retractively by gravity, through the action 75 of spring 33 or in any other manner and pressure on the clamp member 32 is relieved whereby the thread $a-b$ is again free from said clamp device sufficiently to feed forward to the needle. The retractive movement of rod 34 is limited by the interception of its pin 37 by the stop 25.

I am aware that button clamps or work holders have been heretofore so constructed that they could be raised or moved relative 85 to the bed of the machine to facilitate the placing of work or its removal from said button clamp. In my present invention however it is apparent that the button clamp or work holder is given an additional function not heretofore present in such devices 90 and that such function is complementary to the operation whereby the sewing thread is prepared for breaking, by restraining the movement of the thread for the sole and 95 singular purpose of so preparing the thread that the action of the button clamp or any other thread straining device may act to break the thread close to the work, thereby accomplishing not only the additional tightening 100 of the chain or tying stitches but the breaking or severing of the thread so close to the work that subsequent trimming of the thread is unnecessary.

I am aware of various modifications of 105 the means for operating the movable member of the thread clamp in one direction through mechanism operating in conjunction with the driving mechanism for the stitch forming devices. In this respect I 110 may further define and, to some extent, restrict my invention to devices of this nature which operate with or are operated from devices actuated through the driving mechanism to accomplish the clamping or restraining of the needle thread, that when the machine is stopped said thread extends unbroken through the needle and the work around the looper and back to the work so that a complementary strain applied to said 120 thread through an independently operated device may effect the breakage of said thread.

Having thus described my invention I claim as new and desire to secure by Letters 125 Patent,

1. A sewing machine comprising stitch forming means, mechanism for actuating said stitch forming means, a pair of complementary thread breaking devices both located 130

above the work, connections between one of said devices and said actuating means to effect relative movement between said device and the stitch forming means during a series 5 of stitch forming operations and to prevent said relative movement during a chain stitch operation, means operated in conjunction with said actuating means to operate the other of said devices after said chain stitch 10 operation, to restrain the thread, and manually operated means to move said first device to break the thread.

2. A sewing machine comprising stitch forming means, mechanism for actuating 15 said stitch forming means, a pair of complementary thread breaking devices both located above the work, one of which is a button clamp, connections between said button clamp and said actuating means to effect 20 relative movement between said button clamp and the stitch forming means during a series of stitch forming operations and to arrest said movement during another stitch forming operation, means progressively 25 moved by said actuating means to actuate a controlling element of one of said devices whereby said device may be brought into action after said last mentioned stitch forming operation to restrain the thread, and means for operating said button clamp to break the 30 thread.

3. A sewing machine comprising stitch forming means, a work holder, means for manually lifting said work holder, a thread breaking mechanism comprising a thread 35 clamp mounted above the work holder and having a pair of members between which the thread may be engaged, a slide rod, for

means for actuating said stitch forming means, means operated through said actuating means to project said rod its full movement in one direction and to permit the full retraction of said rod during substantially the entire sewing operation, and a spring 45 acting on said thread clamp in opposition to said rod.

4. A sewing machine comprising stitch forming means, a work holder, means for manually lifting said work holder, a thread breaking mechanism comprising a thread 50 clamp mounted above the work holder and having a pair of members between which the thread may be engaged, a spring acting to move one of said members, a slide rod for operating said clamp against the action of 55 said spring, means for actuating the stitch forming devices, and means operated through said actuating means to move said slide rod positively in one direction and to hold said slide rod against retraction. 60

5. A sewing machine comprising stitch forming means, a work holder, means for manually lifting said work holder, a thread breaking mechanism comprising a thread 65 clamp mounted above the work holder and having a pair of members between which the thread may be engaged, a spring acting to move one of said members, a slide rod for operating said clamp against the action of said spring, means for actuating the stitch 70 forming devices, and mechanism for holding said rod from movement and having means operating in conjunction with the stitch forming means to effect the release of said rod to permit its movement.

ROBERT L. LYONS.
